UNITED STATES PATENT OFFICE

2,368,790

PUNCH

Paul O. Unger, Elmhurst, Ill., assignor to Wilson-Jones Company, Chicago, Ill., a corporation of Massachusetts

Application December 23, 1943, Serial No. 515,357

6 Claims. (Cl. 164—91)

This invention relates to a punch for perforating loose sheets of paper or similar material.

It is an object of this invention to provide a durable punch formed from sheet metal with efficient means for adjusting a plurality of punch heads laterally of the punch and for securely maintaining the punch heads in position. It is a further object of this invention to provide a punch with interchangeable gauge means so that the punch heads may be quickly adjusted laterally of the punch with reference to different linear measurements. It is a further object of this invention to provide a punch with a hinged chip pan to facilitate disposal of the chips from the material which is perforated and which will maintain the chips against spilling while the punch is being handled or used. Other objects of this invention will become apparent upon reading the following description, taken in conjunction with the accompanying drawings, in which:

Figure 1 is a top elevation of a punch embodying my invention with parts broken away to facilitate illustration of the punch;

Figure 2 is a top plan view of the reversible linear gauge showing the metric system markings on one surface of the gauge;

Figure 3 is a side elevation of one punch head;

Figure 4 is a longitudinal sectional view taken along the line IV—IV of Figure 1; and

Figure 5 is a cross sectional view through the punch.

In the drawings, the reference numeral 2 indicates a base member to which a chip pan 3 is hinged, as indicated at 4. A strap 5 is provided centrally of the chip pan at the edge opposite the hinge 4, and a latch 6 is secured to the chip pan by means of the strap. The latch has an enlarged head portion 7 which projects through an aperture 8 in the base member and normally overlies one edge of the aperture 8 to maintain the chip pan in closed position. In order to remove the chips from the chip pan it is necessary only to move the latch 6 laterally so that the enlarged head 7 may be depressed through the aperture 8 and that the chip pan 3 may be swung freely around the hinge 4 to empty the pan. The chip pan 3 is also provided with a plurality of cushioned feet 9 so that the bottom of the punch will not scratch or mar the surface of the desk or table on which it is used.

The base member 2 is provided with a channel 10 extending across its entire width and adapted to receive a conventional side gauge 11. The gauge 11 is provided with an upturned end 12, against which the edges of the sheets to be per-

forated are aligned. The base member is provided with another laterally extending channel 13 which is adapted to receive the reversible gauge 14. The gauge 14 is provided adjacent one end with an aperture 15 to facilitate movement of the gauge within the channel 13. One surface of the gauge 14 is marked preferably in inches, as indicated in Figure 1, while the reverse side of the gauge 14 is preferably marked in centimeters, as indicated in Figure 2. Either set of linear markings may be replaced by any other markings desired to indicate any special linear units. The punch base is provided with a center line 16, Figure 1, to facilitate setting the gauge 14 with the zero marking on either surface of the gauge in alignment with the center of the punch.

The base member 2 is provided adjacent its rear edge with an upstanding wall 17. A central cut out portion 18 extends laterally of the wall 17 substantially the entire length of the wall. The base member is also provided with a laterally extending cut out portion 19 which extends substantially across the entire length of the base member.

25 A plurality of punch heads 20 are positioned against the upstanding wall 17. Each punch head 20 comprises a base plate 21, and a back wall 22 integral therewith. A flange 23 integral with the back wall 22 extends forwardly thereof at right angles to said wall. A spacer 24 is positioned on the base plate 21 adjacent the back wall 22. A stripper plate 25 is positioned on the spacer 24 and extends forwardly over the base plate 21. The stripper plate 25 is bent at right angles to form a front wall 26 and is again bent at right angles to provide a top wall 27 which overlies the flange 23 and terminates adjacent the upstanding wall 17. The base plate 21, the spacer 24, and the stripper plate 25 are welded together. The top wall 27 and flange 23 are also welded together to provide a rigid rectangular frame.

The stripper plate 25 and the top wall 27 are provided with registering apertures 28 and 29, in 45 which a punch pin 30 is positioned. A flange 31 is secured to the punch pin 30 underneath the top wall 27, and a coiled spring 32 encircles the punch pin between the flange 31 and the stripper plate 25. After the punch pin has been depressed 50 to perforate sheets inserted in the throat between the base plate 21 and the stripper plate 25 the coiled spring 32 forces the punch pin 30 upwardly as soon as the depressing force is released. The base plate 21 is provided with an aperture 55 33 registering with the aperture 28 and of the

same diameter to receive the cutting end of the punch pin 30 when it is depressed.

The base plate 21 is provided with a center line 34 by means of which it may be adjusted laterally with reference to either the English or metric markings on the gauge 14. When the punch head 20 is in its proper lateral position relative to the punch head, it may be secured in that position by means of a thumb screw 35 which projects through the cut out portion 18 to engage a threaded aperture 36 in the back wall 22. When it is desired to change the lateral position of the punch head, the thumb screw 35 is loosened and the punch head may be easily slid laterally of the base member. If it is desired to remove the punch head from the base member the thumb screw 35 is entirely disengaged from the back wall 22 and the punch head may then be removed.

A flat metal plate 37 welded to the back plate 22 is provided with a threaded aperture 38 forming a continuation of the aperture 36 to provide it sufficient thread to engage the thumb screw 35. The bottom edge of the plate 37 terminates adjacent the stripper plate 25. A back gauge 39 provided with a pair of depending ears 41 is hinged to the plate 37, as indicated at 40, to swing in the plane of the frame of the punch head. The back gauge 39 straddles the stripper plate 25 and the base plate 21 when the back gauge is in the position indicated at Figure 3. This hinged back gauge provided means for quickly and accurately adjusting each punch head to provide a throat with either one or the other of two predetermined depths. When the back gauge is in the position indicated at Figure 5, the spacer 24 determines the depth of the throat and consequently the distance between the edge of the perforated sheets and the perforations. When the back gauge 39 is in the position as indicated at Figure 3, the forward edges of the ears 41 limit the insertion of the sheets in the throat, and thereby provide a different distance between the perforations and the edge of the sheets to be perforated.

The ends of the upstanding wall 17 are bent to provide side flanges 42 which add rigidity to the structure. The top edge of the upstanding wall 17 is bent forwardly to provide a top flange 43. The flange 43 terminates in a hinge 44. An operating handle 45 is secured to the flange 43 by means of the hinge 44. The operating handle is provided with a cut out portion 46 which is large enough to permit the insertion of the user's fingers in order to facilitate operation of the handle. The handle is provided with a downturned flange 47 around its outer edge and a similar flange 48 around the cut out portion 46 to provide rigidity and to give the handle a smooth finished appearance.

Although I have described a preferred embodiment of my invention in detail, it will be understood that the description thereof is illustrative,

rather than restrictive, as many details may be modified or changed without departing from the spirit or scope of my invention. Accordingly, I do not desire to be restricted to the exact construction described, except as limited by the appended claims.

I claim:

1. In a punch, a base member, a reversible gauge slidably secured to said base member, a punch head provided with means adapted to cooperate with markings on either surface of said reversible gauge to position said punch head laterally relative to said base member, and a thumb screw operable to maintain said punch head in said adjusted position.
2. In a punch, a punch head including a base plate, a back plate and a top flange formed of one continuous strip of sheet metal, a spacer positioned on said base plate, and another strip of sheet metal bent to form a stripper plate positioned over said spacer parallel to said base plate, a front wall and a top wall, said base plate, spacer, and stripper plate being welded together, and said top plate and top flange being welded together to form a rigid frame, a flat metal plate welded to said back plate, and a back gauge hingedly secured to said last mentioned plate.
3. In a punch, a punch head formed of two strips of sheet metal bent to form a rectangular frame, one of said strips having a portion constituting a stripper plate and said other strip having a portion constituting a base plate, said stripper plate overlying said base plate, a spacer positioned between said base plate and said stripper plate, and a back gauge hinged to swing in the plane of said frame and adapted to straddle said stripper plate and said base plate.
4. In a punch, a base member, an apertured upstanding wall secured to said base member, and a punch head provided with a back plate positioned adjacent said upstanding wall, said back plate having a threaded aperture registering with the aperture in said upstanding wall, whereby a thumb screw engaging said threaded aperture through said aperture in said back wall is operable to secure said punch head adjacent said upstanding wall.
5. In a punch, a base member, and a reversible gauge slidably secured to said base member, said gauge being marked in linear units on one surface and in linear units of a different system on the opposite surface, whereby punch heads secured to said base member may be adjusted laterally of said base member according to either system of linear measurement.
6. In a punch, a punch head including a stripper plate and a back gauge hinged transversely of said stripper plate adjacent thereto, said back gauge having a pair of downturned ears adapted to straddle said stripper plate when said back gauge is in operating position.

PAUL O. UNGER.
